DESIGN FOR A HANDLE BAR FOR A VELOCIPED OR THE LIKE

John G. Rideout, Cleveland, Ohio, assignor to
Junior Toy Corporation, Hammond, Ind., a cor-
poration of Indiana

Application March 20, 1942, Serial No. 106,263

Term of patent 7 years

To all whom it may concern:

Be it known that I, John G. Rideout, a citizen of the United States of America, residing at Cleveland, in the county of Cuyahoga and State of Ohio, have invented a new, original, and ornamental Design for a Handle Bar for Velocipedes or the like, of which the following is a specification, reference being had therein to the accompanying drawing forming a part thereof, wherein:

Figure 1 is an elevational view of a handle bar for a velocipede or the like, showing my new design;

Figure 2 is a top plan view of the design illus-
trated in Figure 1; and

Figure 3 is a side elevational view thereof.

I claim:

The ornamental design for a handle bar for a velocipede or the like, substantially as shown.

JOHN G. RIDEOUT.
